C. L. KELLER

ROOFING

Filed Nov. 30, 1923

INVENTOR:

Charles L. Keller

BY

Albert Keller

ATTORNEYS:

UNITED STATES PATENT OFFICE.

CHARLES L. KELLER, OF CINCINNATI, OHIO, ASSIGNOR TO THE RICHARDSON COMPANY, OF LOCKLAND, OHIO, A CORPORATION OF OHIO.

ROOFING.

Application filed November 30, 1923. Serial No. 277,642.

To all whom it may concern:

Be it known that I, CHARLES L. KELLER, a citizen of the United States, and a resident of Cincinnati, in the county of Hamilton and State of Ohio, have invented certain new and useful Improvements in Roofing, of which the following is a full, clear, and exact description, reference being had to the accompanying drawing, forming part 10 of this specification.

My invention relates to devices and shingle structures employed in the laying of roofs, and in roofs as formed thereby. It relates more particularly to the provision 15 of an interrelation between shingles and metallic shingle securing devices, whereby a roof of adequate coverage, with each shingle locked down to the roof at the butt can be provided.

20 It has been proposed by John A. Topping in his Patent No. 1,430,338, dated September 26, 1922, to provide a securing device for shingles which acts as a nailing device for shingles, and also as forming a loop or pocket into which the butt end of a shingle can be inserted, said loop spanning the top of the shingle. In my invention I employ the Topping devices and general method of laying.

25 It is my specific object to provide a shingle in which certain notches and projections are formed, these serving as guiding means whereby a roof of the Topping character can be laid more expeditiously, and with greater certainty of being uniform in exposure and roof coverage. Another object is to provide 30 a notch in which the attaching device finds engagement, whereby considerable expansion and contraction are allowed for.

35 In the forming of composition shingles by the usual factory processes, or by any process with which I am familiar, it is not possible to assure an absolute accuracy to the extent that the dimensions of each shingle are the same. The stretching of the 40 felt, due to differences of temperature, plasticity and composition, and hence varied action of the cutting knives throughout a run of a shingle cutting machine, result in 45 the inaccuracies of size referred to, the most disadvantageous one in the type of roof

referred to herein, being that all of the shingles are not perfectly rectangular or square. By my invention the shape of the shingle is not used as the guide in laying, 55 but instead the location along the edges thereof of certain small notches and projections. These notches and projections can be definitely spaced, and the margin of error in the relative placing of the same in 60 each shingle is very low. Accordingly by my invention I not only provide a readily followed guide in laying, but I also provide means by which inaccuracies of shape of the shingles do not hamper the accuracy of 65 placing them on the roof, and hence an accumulation of error, resulting where course after course is laid following an error which has arisen in a earlier course. In an ordinary shingle application there is more 70 latitude in placing of the shingles than in a roof where the securing device requires a definite placing of each shingle, with relation to the ones preceding it, and hence this improvement now recited, is of great 75 value in connection with roofs laid by means of specially formed attaching devices which demand a definite relation of shingles throughout the roof.

I accomplish the objects above noted by 80 that certain construction and arrangement of parts to be hereinafter more specifically pointed out and claimed.

In the drawing:

Figure 1 is a plan view of one of the shingles used by me.

Figure 2 is a plan view of a roof section laid according to my invention.

Figure 3 is a perspective of one of the attaching devices.

The shingle used by me is shown individually in Figure 1, having a rectangular body 1, two notches 2, 2, cut into one edge, and two projections 3, 3, at the opposite edges, the notches and projections being 90 along lines diagonal of the shingle since the shingles are to be laid diagonally. The shape of the notches and projections is preferably V-shaped, although this is not a requisite, and they are small and inconspicuous. In making the shingles the notches 95 cut out of one shingle when being cut from

a sheet, form the body of the projections on the next adjacent shingle.

The attaching device used has two arms 4, 4, and a cross piece 5, formed by a forty five degree angle bend of the metal at 6, 6. The nail holes 7, 7, are used in nailing the device to the roof.

The roof plan has been used in some respects as a diagram for use in explanation 10 of a method of laying. As will be noted, the shingles are started off by a first course of shingles A, which are set at a forty five degree angle to the eave line of the roof, with their corners touching each other. The 15 attaching devices are then set in place to straddle the upper end of the V-shaped opening between the shingles, with one leg on the corner of the two adjoining shingles forming the angle. The shingles of the 20 next course B, are set with their angle points, or butts, slipped in under the portions 5 of the attaching devices.

The positioning of the notches and projections are made with relation to the size of 25 the attaching devices used, so as to result in the functions to be now described.

Referring to the shingles marked D and E, in the diagram, it will be noted that the attaching device is set in place with the left 30 hand corner at the apex of the notch D², and with the right hand leg pointed direct to the projection E¹ on the shingle E. This will bring the attaching device into true position, and nails driven first through one leg 35 and then through the other, will position the attaching device or "lock" properly, and hold down the corners of the two shingles through which the said "lock" is nailed.

The shingle F is then applied by slipping 40 its lower corner into the cross strap of the lock. The roofer can then guide the shingle F to proper position since three points are provided for. Thus the projection F³ will lie over the edge of the shingle D. The edge 45 of the shingle F will coincide with the notch D² by means of which the attaching device was guided, and has been described. The edge of the shingle F will also coincide with the position of the upper projection E² of 50 the shingle E.

In addition to the above the notch F² of the shingle F will lie in the attaching device, which gives the shingle F a chance to expand and contract in normal degree without buckling, since the notch provides for some play.

Referring to the shingle G, it will be noted that should its edges be as indicated by the dotted line G¹, forming an obtuse angle, that 60 the displacement of the upper left hand projection G², would be out of true position a very slight amount, this amount being mainly along the arc of a circle having its center at the left hand corner of the shingle, 65 while its position along the diagonal pass-

ing through the notch G², and the said projection G² would be affected very little.

It will be noted that by my invention, I have cut down chances of error in the roof due to untrue shape of the shingles. I have 70 provided a guide by means of which a true forty-five degree angle can be given to the shingle without reliance upon the unguided eye, and in which backlap is fixedly obtained. I have provided a means for expansion and 75 contraction, and I have provided a guide for use in application of the attaching device. I have thus substantially cut down the undesirable points of a roof which is confined 80 positively in laying, and in use by inflexible securing devices, which have a definite relation to two or more shingles, while preserving the good ones, which are increase of area 85 of exposure without danger of improper coverage, secureness of all units in place at all times, and protection against curling of the exposed butts, and possibility of using a thinner material of more flexibility and hence less expense to manufacture, as well as easier to force to conform to irregularities of 90 an old roof surface.

Having thus described my invention, what I claim as new and desire to secure by Letters Patent, is:—

1. A roofing unit formed of a shingle and an attaching device, having two interspaced arms and a pocket forming portion to engage the corner of a shingle thrust into it, from above, and said shingle being of rectangular shape and having a series of edge mutilations arranged on lines crosswise of the shingle, and located inward from the corners thereof to guide the position of the pocket formed portion of the attaching device.

2. A roof formed of shingles having a general rectangular shape, and laid at an angle so that the corners of the shingles in a course are brought adjacent to each other, attaching devices having arms nailed down to the adjacent corners of shingles in a course, said arms providing between them for a pocket into which the corner of a superimposed shingle is to be placed, said shingles formed with edge mutilations arranged in lines crosswise of the shingles, and spaced inwardly from the edges so as to define the position of the pocket forming element of the attaching device.

3. In a roofing unit for use with an attaching device of the character described, a body portion adapted to be laid with its edges at an angle to the roof lines, and said body portion having mutilations at its edges arranged on lines at a like angle to the body thereof, for the purpose of indicating the lines of proper disposal of said unit with relation to other units on a roof, said mutilations being spaced inwardly from the corners of the shingle the distance of desired 120

overlap of the courses in a roof formed thereof.

4. In a roofing unit for use with an attaching device of the character described, a body portion adapted to be laid with its edges at an angle, said body portion having two notches at one edge and two projections at

the opposite edge, same being arranged in lines across the shingle at a like angle, and same being also placed inwardly from the corners of the shingle a distance equal to the desired overlap of the shingles when laid in courses. 10

CHARLES L. KELLER.
